US0D1101252S

(12) **United States Design Patent** (10) **Patent No.:** **US D1,101,252 S**
(45) **Date of Patent:** **** Nov. 4, 2025**

(54) **LAMP COVER**

(71) Applicant: **Brown & Watson International Limited**, Hwaseong-si (KR)

(72) Inventor: **Sang Min Jeong**, Gwacheon-si (KR)

(73) Assignee: **BROWN & WATSON INTERNATIONAL LIMITED**, Hwaseong-si (KR)

(**) Term: **15 Years**

(21) Appl. No.: **29/930,607**

(22) Filed: **Mar. 1, 2024**

(30) **Foreign Application Priority Data**

Oct. 12, 2023 (KR) 30-2023-0039838

(51) LOC (15) Cl. **26-05**

(52) U.S. Cl.

USPC **D26/139**

(57) **CLAIM**

The ornamental design for a lamp cover, as shown and described.

DESCRIPTION

FIG. 1 is a top-front-left perspective view of a lamp cover showing my new design;

FIG. 2 is a top-rear-right perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of the portion 9 of FIG. 1.

The broken lines in FIGS. 1 and 9 are for the purpose of illustrating the boundary of the enlarged view and form no part of the claimed design.

1 Claim, 6 Drawing Sheets
